RAYMOND R. OLSON, OF LONG BEACH, CALIFORNIA

WATCH CLEANING MACHINE

Application filed September 21, 1931. Serial No. 584,230.

The object of this invention is the provision of a machine for cleaning watch works and the like, which is characterized by simplicity in construction and reliability and efficiency in practical use.

The invention will be fully and comprehensively understood from a consideration of the following detailed description when read in connection with the accompanying 10 drawings which form part of the application, with the understanding, however, that the improvement is capable of extended application and is not confined to the exact showing of the drawings nor to the precise 15 construction described and, therefore, such changes and modifications may be made therefrom as do not affect the spirit of the invention nor exceed the scope thereof as expressed in the appended claims.

20 In the drawings:

Figure 1 is a side elevation of a watch cleaning machine in accordance with this invention, parts being in section.

Figure 2 is a fragmentary top plan view 25 thereof.

Figure 3 is a sectional view approximately on the line 3—3 of Figure 1.

Figure 4 is a detail sectional view through the motor support taken approximately on 30 the line 4—4 of Figure 1.

Figure 5 is a plan view of the main elements of the motor support.

Figure 6 is a plan view of the disc employed.

35 Figure 7 is a sectional view approximately on the line 7—7 of Figure 3.

Figure 8 is an inverted plan view of a construction disclosed by Figure 7.

Figure 9 is a side elevation of the basket 40 with the spider at the top thereof in section.

Figure 10 is a sectional view approximately on the line 10—10 of Figure 1 with the disc removed.

45 Figure 11 is a sectional view approximately on the line 11—11 of Figure 1.

As disclosed by the drawings the machine includes a base plate 1 that is provided with compressible feet 2. The base is centrally provided with an opening surrounded by a 50 boss 3 and in this opening there is securely

fixed the tubular standard 4 of the machine. The standard 4 extends a suitable distance above the base and has its top end closed by a screw cap 5.

Resting on the upper face of the boss 3 55 there is another boss formed on the under face of a plate 6. The plate 6, in its upper face, is provided with three equidistantly spaced annular depressions 7, each affording a rest for a receptacle 8. The receptacles 8 60 are of crockery, glass or like material and as the same are of cup-shaped formation they will hereinafter be referred to as cups. The supporting plate 6 for the cups is centrally formed with a tubular projection 9 that surrounds the opening through which the standard passes, and received in this tubular extension and preferably fixed thereto there is a sleeve 10 of a greater length than the height 65 of the cups 8. The sleeve 10 is held from longitudinal movement on the standard, and also in contact with the bearing boss 3 by a collar 11 arranged around the standard and held in contact with the upper end of the sleeve by a binding element 12. Through the hollow 70 sleeve there is passed the cord 13 that encloses conductor wires, one end of the cord being plugged to a wall socket or the like and the other end of the cord having its wires connected to a motor of the ordinary type, and the casing for this motor is indicated in the drawings by the numeral 14. The motor is sustained in a vertical position as disclosed by the drawings and has its bottom portion provided with an elongated neck extension 15 75 to afford a firm bearing for the motor shaft 16. On the top of the casing there is a knob 17 in the nature of a turnable switch for controlling or shutting off the current to the motor.

The mount or support for the motor is of a particular and peculiar construction and forms an important feature of this invention. The mount is in the nature of a gimbal, the same including a flat ring 18 that loosely receives the motor casing therethrough, the said casing being provided with diametrically opposed angle brackets 19 that are suitably spaced from the ring 18 and that have preferably loosely passed therethrough bolts 20 en- 80 85 90 95 100

gaged by nuts, and the bolts 20 pass through the bores of rubber or like compressible discs 22 while similar discs 23 are forced against the under face of the ring 18 by the nuts 24 that are screwed on the bolts 20.

5 The second element of the support is arranged below the ring and is in the nature of a forked plate 25. The plate 25 is out of contact with the metal casing and the ends thereof are provided with openings that register with similar openings in the ring 18, and through these openings there are passed bolts 26 engaged by nuts 27. The bolts pass through rubber or like compressible washers 15 28 that are disposed between the arms of the element 25 and the sides of the ring 18 and which discs are arranged at right angles with respect to the compressible discs 22 and 23. Other elastic or rubber discs 29 are supported by the bolts 26 on the upper face of the ring 20 18, being held in place by the nuts 27.

The connecting end for the arms of the forked support 25 is concaved and flanged, as at 30, and is bolted or otherwise secured to a 25 slide 31 on the standard 4. The standard 4 is formed with a longitudinal groove 32 and in the bore of the slide 31 there is a key 33 that is received in the said groove. There is passed through a threaded opening in the 30 slide 31 a headed binding bolt 35 which contacts with the standard and holds the motor 14 at desired elevations with respect to the said support. The outer end of the motor shaft 16 is threaded and has screwed thereon 35 an open element which I will term a spider and which is indicated by the numeral 36. The lower portion of the spider is in the nature of a ring 37 formed with exterior threads and these threads are designed to be 40 screwed in a metal ring member 38 that forms the top element of the open frame 39 for a reticulated basket 40. Resting on the top of the element which I have termed the spider 36 and loosely arranged on the shaft 37 there 45 is a disc 41 that has on its outer face a boss or tubular enlargement 42 to steady the same on the said shaft. In each of the cups 8 there are right-angularly arranged spaced baffle or 50 agitator plates 43. The plates are vertically arranged and lie approximately in planes passing the center of the cups 8, and resting on the plates 43 there is a disc 44 whose central opening 45 is arranged in a line with the inner edges of the said plates 43.

55 The cup supporting plate 6 is provided on its under face with three spaced circumferentially arranged depressions or sockets 46, each being surrounded by a depending boss 47 that rests on the base 1.

60 The under face of the base is provided with spaced bearings 48 for a shaft 49. The bearings 48 are preferably formed on the ends of a plate 50 which is riveted on the under face of the base, and the shaft 49 has its inner 65 end formed with an offset finger 51 provided

with a seat or lug 52 that passes through an opening in the said base and is designed to be received in one of the sockets 46. The second or outer end of the shaft has fixedly secured thereon a handle 53 and there is fixed on the shaft, adjacent one of the bearings 48, one end of a coil spring 54, the second end of the said spring being brought into contact with the plate 50, whereby the element 52 on the shaft is at all times influenced through its opening and into the socket 46. By this arrangement it will be noted that one of the cups 8 is at all times sustained in a position to receive the basket 40 therein and through the central opening in the discs 44.

All of the cups 8 have deposited therein watchwork cleansing agents. The cleansing fluid in one of the cups consists of water, soap and ammonia, that in another cup being of some non-explosive cleaning solvent similar to gasoline and that in the remaining cup being of carbon tetra-chloride. The slide is permitted to move downwardly to arrange the basket and the watchworks contained therein in the first cup. The disc 41 on the motor shaft 16 will contact with the disc 44 in the cup or jar 8 and will thus cover the opening 45 in the said disc 44. The motor rapidly revolves the basket for say two minutes in the cleansing fluid. The slide is then operated to raise the basket out of the cup or jar and the motor is again rapidly revolved when the basket is in the air to spin the said basket and this centrifugal motion will dry the basket and the watchworks 100 therein. The latching means is operated while the basket is elevated to bring the next cup or jar into a position to receive the basket and watchwork in such cup and the operation above described is repeated. The watchworks 105 are subject to the same treatment in all of the cups or jars and likewise to the rapid centrifugal action when raised out of the jars to thoroughly dry and effectively clean the watch. When the basket is lowered into the 110 cups or jars and the disc 41 rests on or covers the openings in the discs 44 the rapid rotation of the basket by the motor will, of course, agitate the cleansing agent in the cup or jar, this agitation being materially assisted by the 115 baffle plates 43, but the agitated fluid cannot flow out of the cup or jar because the said jar is practically sealed by the discs 41 and 44. This it will be noticed, is an important feature of the invention. The gimbal mounting for the motor permits of the shaft 16 being revolved at a greater rate of speed than is ordinary and allows the basket to turn between 7,500 and 10,000 revolutions per minute so that the cleansing solution is rapidly and effectively thrown off of the watch and out of the basket when the basket rotates in the air and likewise the watch is rapidly rotated when in its cleansing bath. This high speed is made possible only by the 120 125 130

gimbal support. As long as everything is in balance the elastic mounting is not necessary but as soon as the watch is put in the basket throwing the basket out of balance the vibration would prevent high speed. With the mounting, however, the basket is permitted to revolve upon its center of gyration instead of its geometric center. As above stated, the lower neck or bushing 15 for the motor casing 10 is longer and heavier than those usually employed and this prevents whipping of the shaft from its high speed when the basket is out of balance.

Having described the invention, I claim:—

15 1. In a watch cleaning machine, a cup adapted to contain a cleaning fluid, baffle plates in the cup, a disc resting on the baffle plates and having an opening therethrough, a high speed motor having its case mounted 20 for vertical movement above the cup, a reticulated basket affording a receptacle for the watchworks on the shaft of the motor, and a disc loosely mounted on the motor shaft above said basket to rest upon the disc in the 25 cup when the basket is lowered into the cup through said opening.

2. A watchworks cleaning machine, including a cup for a cleaning fluid having vertically disposed spaced baffle plates rising 30 from the bottom thereof and terminating away from the open top thereof, a disc resting on the baffle plates, said disc having an opening therein to receive the basket, a high speed motor having its case supported for 35 vertical movement above the cup, a reticulated basket for the watchworks on the shaft of the motor, a disc loose on the motor shaft above the basket and designed to rest on the disc in the cup when the basket is positioned 40 between the baffle plates in the cup, and a mount for the motor.

3. A watchworks cleaning machine, including a cup for a cleaning fluid having vertically disposed spaced baffle plates rising 45 from the bottom thereof and terminating away from the open top thereof, a disc resting on the baffle plates, said disc having an opening therein to receive the basket therethrough, a high speed motor having its case 50 supported for vertical movement above the cup, a reticulated basket for the watchworks on the shaft of the motor, a disc loose on the motor shaft above the basket and designed to rest on the disc in the cup when the basket 55 is positioned between the baffle plates in the cup, and means for holding the motor in vertical adjusted positions.

In testimony whereof I affix my signature.
RAYMOND R. OLSON.
